UNITED STATES PATENT OFFICE

FRED OSSING, OF CLEVELAND, OHIO

ROLLER AND KEY FOR PRINTING PRESSES

Application filed April 13, 1929. Serial No. 354,804.

This invention relates to improvements in inking rollers for printing presses and particularly to an improved shaft construction for such rollers.

5 The rollers in common use on what are known as job presses comprise a steel shaft on which is cast a resilient roller, the roller being a glue-gelatine composition or specially prepared rubber. Slidably received on the 10 ends of the roller shaft are guide rollers which operate on guides or roller-ways at each side of the press. The movement of the guide rollers over these guide-ways rotates the resilient rollers. The guide rollers are 15 removable from the shaft by merely sliding them longitudinally and are prevented from rotating on the shaft when slid into place by projections which are struck out of the shaft itself, the guide roller having a key-way into 20 which one of the projections fit.

After being used for sometime the rollers become dead and must be recast, the same shaft being used over and over again. It has been found that the projections which are 25 struck from the shaft itself are soon worn or broken off and the shaft rendered useless.

It is the object of my invention to provide a shaft construction which includes a removable key of a particular form which may be 30 readily replaced when worn so that the shaft of the roller may be used indefinitely.

A further object is to provide a key which may be held in place by the roller which is cast thereabout, and onto which the guide 35 roller is easily engaged or disengaged.

A still further object is to provide an inking roller with a shaft having shoulders against which the guide rollers abut to properly space them, such shoulders being more 40 permanent than the expedients heretofore used for that purpose.

In the drawings Fig. 1 is an elevation of 45 an inking roller with the shaft and key constructed in accordance with my invention, one end being shown in section; Fig. 2 is a longitudinal view through one end of the shaft; Fig. 3 is a transverse section on the line 3—3 of Fig. 2; and Fig. 4 is a perspective view of an end portion of the shaft with the 50 key separated therefrom.

In describing my invention, reference will be had to the accompanying drawing wherein like parts in the several views are indicated by like reference numerals, and in which 10 designates generally the inking roller of an 55 ordinary job-press. The roller includes a steel shaft 11 with the ordinary composition or rubber roller 12 cast thereon. At each end the shaft 11 is reduced as at 13 to provide a shoulder 14 against which the guide roller 15 60 of the roller truck engages to position them in proper relation to the guide rails 16 on which they are adapted to roll.

To prevent rotation of the guide roller on the shaft end 13 a key 17 is provided over 65 which the roller, which is provided with a key-way 18, engages.

To receive the key 17 which is of a peculiar construction particularly suitable for use on printing rollers, the shaft 11 is provided with a key-way 20 at each end adjacent the shoulders 14, the key-way being cut for the most part in the large part of the shaft. The shaft is also provided with two parallel apertures 21 and 22, one extending through 70 the shaft from the bottom of the key-way 20 while the other extends through the reduced end of the shaft and at a short distance from the shoulder 14.

The key 17 has integral lugs or projections 80 24 and 25 extending laterally therefrom and spaced to fit in the apertures 21 and 22 respectively when the key 17 engages in the key-way 20. It will be noted that the outer end of the key 17 extends out of the key-way 85 20 and the side edges of the inner portion of the key 17 fit within the key-way. In the form illustrated the body portion of the key 17 is rectangular in cross-section so that the greatest amount of surface is presented 90 against which the guide roller 15 may bear. The key so made fits snugly in the key-way 20 and when the roller 12 is cast thereabout is prevented from being accidentally displaced when the guide rollers are removed. 95 Should it be necessary to replace the key it may be easily removed since the apertures 21 and 22 provide access for a punch which may be used to disengage the key from its seat.

In the structure as above described a sub- 100

stantial key is provided on which the guide roller may engage and the shoulder 14 provides a permanent stop to limit the inward movement of the guide roller.

5 Having thus described my invention, what I claim is:

1. In a printing roller, a shaft having a reduced end providing a shoulder and a key-way in the larger portion of the shaft cutting 10 said shoulder, the smaller portion of the shaft having a diametrically disposed aperture therethrough, one end being in alignment with said key-way, and a key received in said key-way and having a lateral projection received in said aperture, said shaft having thereon a relatively thick covering of gum rubber, said key being partially covered by said layer of rubber.

2. In a printing roller, a shaft having a 20 reduced end providing a shoulder and a key-way in the larger portion cutting said shoulder, said shaft having an aperture extending from the bottom of said key-way diametrically therethrough, the smaller end of said 25 shaft having an aperture extending diametrically therethrough, one end of which is in alignment with said key-way, and a key having one end received in said key-way and having lateral projections received in said 30 apertures for the purpose described, said shaft having thereon a relatively thick covering of gum rubber, said key being partially covered by said layer of rubber.

3. In a printing roller, a shaft adapted to 35 receive a guide roller and having spaced parallel apertures extending diametrically therethrough, a key having lateral projections received in said apertures, a guide roller received on said shaft having a recess into 40 which said key extends and means for limiting the longitudinal movement of said guide roller on said shaft in one direction, said shaft having thereon a relatively thick covering of gum rubber, said key being partially covered by said layer of rubber.

4. In combination a shaft on which a member is to be non-rotatably secured having a key-way, an aperture extending therethrough from the bottom of said key-way, and a second aperture extending therethrough adjacent one end of said key-way and with one end aligned therewith, and a key received in said key-way and provided with lateral projections received in said apertures, said shaft having thereon a relatively thick covering of gum rubber, said key being partially covered by said layer of rubber.

5. In combination with a shaft on which 60 a member is to be non-rotatably secured having a pair of apertures extending diametrically therethrough and a key on which said member engages provided with laterally projecting lugs received in said apertures, said 65 shaft having thereon a relatively thick cov-

ering of gum rubber, said key being partially covered by said layer of rubber.

In testimony whereof, I hereunto affix my signature.

FRED OSSING.
